UNITED STATES PATENT OFFICE

C. ROY GLEASON, OF CHICAGO, ILLINOIS

TANK FOR CHROMIUM PLATING

Application filed June 3, 1927, Serial No. 196,189. Renewed March 14, 1930.

In the practice of electro-deposition of chromium it is difficult to make a tank for the electrolyte that will resist the action of chromium plating solutions. When the tank 5 itself is attacked by the electrolyte there is deterioration in the tank as a structure and a waste of solution, and the electrolyte may also acquire additions that will reduce its efficiency and cause the quality of the work 10 to be lowered. Thus, for example, a wooden tank is quickly rendered useless by the action of the usual chromium plating solutions, whereas a tank of iron not only depreciates but brings about the introduction of an ob- 15 jectionable amount of iron compounds in the plating bath. Furthermore, the anodes, the tank and the electrolyte often create of them-selves an electrolytic cell that serves no useful purpose but whose action is simply injurious and wasteful. So, also, wasteful stray 20 currents often find their way between anode and tank and between cathode and tank.

The object of the present invention is to produce a simple, novel, rugged and compar- 25 atively inexpensive tank for holding the electrolyte used in the process of chromium plating or electro-deposition of chromium as such, which will not be attacked by the chromium plating solutions and will therefor not de- 30 teriorate nor introduce objectionable com- pounds into the solutions, and which will pre- vent waste and destructoin from current flow in directions and along paths other than those serving a useful purpose.

If those surfaces in a tank that are in contact with the electrolyte are made of glass, the objections heretofore enumerated will be overcome. It is, however, difficult to produce a glass tank that will be serviceable for 40 commercial electro-deposition of metals on a large scale and the plating of large objects. I therefore propose to construct a tank of a material having the requisite mechanical strength and ruggedness, and line this tank 45 with sheets of glass accurately fitted together. If care is taken in the shaping of the sheets or slabs of glass reasonably tight joints may be obtained without packing or cement of any kind and, in any event, the joints will be tight 50 enough for all practical purposes.

If the temperature of the electrolyte, in the process of chromium deposition, is desired to be at room temperature at the start of the process and thereafter is left to take care of itself, the uniformity and quality of the work 55 will not be as good as though the temperature were controlled to fit the needs of any particular case. A further object of the present invention is to produce a simple and novel means for effectively controlling the tempera- 60 ture of the electrolyte so as to permit the operator to secure and maintain, at will, any desired temperature and avoid unevenness in the temperature during the plating operation.

The various features of novelty whereby 65 my invention is characterized will herein- after be pointed out with particularity in the claims; but, for a full understanding of my invention and of its objects and advantages, reference may be had to the following 70 detailed description taken in connection with the accompanying drawing, wherein:

Figure 1 is a top plan view of a tank ar- ranged in accordance with my invention; Fig. 2 is a view of the tank partly in elevation 75 and partly in section; Fig. 3 is a vertical sec- tion through the bottom portion of a modi- fied form of tank; Fig. 4 is a vertical sec- tion through still another form of tank, only a fragment being shown; and Fig. 5 indicates 80 diagrammatically automatic temperature controlling means.

Referring to Figs. 1 and 2 of the drawing, 1 represents a rectangular steel tank of any suitable size. Beneath the tank are support- 85 ing feet 2 of porcelain or other insulating material. Around the top of the tank is a flange 1^a projecting outwardly therefrom. The tank is lined with a thin layer 3 of lead over which are laid sheets or plates 4, 5 and 6 90 of glass. The glass is preferably wire glass, as indicated in Fig. 2, to prevent displace- ment of the fragments in case a sheet or plate is broken. Furthermore, the wire should be uncoated and not of the zinc coated type or- 95 dinarily employed in the manufacture of wire glass. In assembling the structure, the end and the side plates are fitted in, then the bottom plate is lowered into place. If the plates are smooth, that is, have plane sur- 100

faces, then by finishing the edges accurately, comparatively tight joints are obtained; and there will not be enough leakage of solution or of current to be harmful. If necessary, the joints may be cemented with any suitable material.

Upon the flange are laid wooden, fibre, bakelite or phenol resins, or any suitable insulating strips 7 and 8, the side and end plates preferably extending up past the inner edges of these strips into the plane of the tops of the strips. The strips may be secured to the flange by fastening devices 9, if desired. The glass is held in place by means of clamping hooks 10 secured to the strips and hooked over the upper edges of the side and end plates.

Bus bars A, A and B, when laid across the top of the tank, are insulated from each other and from any electrically conductive part of the tank by the insulating strips, or the glass, or both, and may be held in place by clamps or any other suitable means.

For the purpose of controlling the temperature of the solution, the tank may be jackeded or one or more pipes containing a cooling medium or a heating medium, or both, may be placed in the tank. In the arrangement shown there are in the bottom of the tank two U-shaped pipes 11 and 12 provided with risers 13 and 14 extending to and above the top of the tank near one end. One of these U-shaped pipes is adapted to contain a heated fluid or steam while the other is adapted to contain a cooling fluid. By controlling the flow of the fluids or steam through these pipes, the temperature of the bath may be controlled and, particularly, it may be maintained more uniform throughout than would ordinarily be the case. The coils must be impervious to the plating solutions and may therefore be made of lead, or of steel, glass enamelled, or coated with like materials.

The pipes must be insulated from each other, from the metal of the tank and from the supply pipes leading thereto. In the arrangement shown, the pipes rest on bars 15 composed of insulating material not affected by chromium solutions; the risers are held in place by clamps 16 also composed of insulating material not affected by chromium solutions; and in each riser or between each riser and its supply pipe is arranged an insulating section or coupling 17.

In the arrangement shown in Fig. 3 the lead lining is omitted, at least at the bottom. There is a cooling pipe 20 within the tank, and heat is adapted to be supplied to the bath by means of a burner 21 arranged underneath the tank. In order to prevent cracking of the bottom glass sheet or plate 22 through contact with the hot metal bottom of the tank, I raise this sheet or plate above the metal bottom so as to leave a space between

the two. The sheet or plate 22 is held in its raised position by means of supporting spacers 23 that are preferably made of a material that is a poor conductor of heat and is not readily attacked by the electrolytes used in electro-deposition of metals.

In another adaptation of my invention, the body of the tank may be made of wood. Thus in Fig. 4 there is shown a wooden tank 25 lined with lead 26 and then with glass sheets or plates 27. In this case heat regulation may be affected in the manner shown in Figs. 1 and 2.

The temperature of the bath may be controlled automatically. Thus there may be a single heat interchanging pipe in the tank, this pipe being supplied with a heating or cooling medium whose temperature is controlled. A simple means of accomplishing this is illustrated in Fig. 5 wherein 30 represents either of the pipes 11 and 12 in Fig. 1 or the pipe 20 in Fig. 3. The pipe 30 is adapted to receive hot and cold water or stream from the pipes 31 and 32, respectively. Between these three pipes is a thermally-controlled valve 33 of any usual or suitable construction, whereby water of any desired temperature may be caused to flow through temperature regulating pipe 30.

While I prefer a glass lining, in some cases bakelite, or any phenol resin material, porcelain, vitreous enamel, pyrex glass or hard rubber sheets may be used as a tank lining instead of glass.

While I have illustrated and described with particularity only a single preferred form of my invention, with slight modifications, I do not desire to be limited to the exact structural details thus illustrated and described; but intend to cover all forms and arrangements which come within the definitions of my invention constituting the appended claims.

I claim:

1. A tank for containing the electrolyte for use in the electro-deposition of chromium, comprising a container composed of any suitable material and a lining of lead and then lined with glass.

2. A tank for containing the electrolyte for use in the electro-deposition of chromium, comprising a wooden container, a lead lining in the container, and a glass covering over the lead for contact with the electrolyte.

In testimony whereof, I sign this specification.

C. ROY GLEASON.
